UNITED STATES PATENT OFFICE.

OLIVER C. RITZ WOLLER, OF CHICAGO, ILLINOIS.

DESIGN FOR AN AUTOMOBILE LENS.

Application filed March 14, 1925. Serial No. 12,727. Term of patent 14 years.

To all whom it may concern:

Be it known that I, OLIVER C. RITZ WOLLER, a citizen of the United States, residing at Chicago, in the county of Cook and State of Illinois, have invented a new, original, and ornamental Design for an Automobile Lens, of which the following is a specification, reference being had to the accompanying drawing, forming part thereof.

I claim:

The ornamental design for an automobile lens, as shown.

In testimony whereof I affix my signature at 10 South La Salle Street, Chicago, Illinois.

OLIVER C. RITZ WOLLER.
